UNITED STATES PATENT OFFICE

155,928

DESIGN FOR A COMBINED PIN AND CONTAINER OR SIMILAR ARTICLE

Richard L. Sandefur, Central Islip, N. Y., assignor
to Sandefur-Burke, Inc., Bethpage, N. Y., a cor-
poration of New York

Application July 30, 1948, Serial No. 147,849

Term of patent 14 years

(Cl. D45—19)

To all whom it may concern:

Be it known that Richard L. Sandefur, a citizen of the United States, and a resident of Central Islip, in the county of Suffolk and State of New York, has invented a certain new, original, and ornamental Design for a Combined Pin and Container or similar article described and claimed in the following specification and shown in the accompanying drawings, wherein:

Fig. 1 is a plan view of the combined pin and container embodying the present design;

Fig. 2 is a side elevation thereof; and

Fig. 3 is a side elevation of the combined pin and container taken at right angles to Fig. 2.

What is claimed is:

The ornamental design for a combined pin and container or similar article, substantially as shown.

RICHARD L. SANDEFUR.
